(57) **CLAIM**

I claim the ornamental design for a pet feeder, as shown and described.

DESCRIPTION

FIG. 1 is a top, front, right perspective view of a pet feeder of my new design;

FIG. 2 is a bottom, back, left side perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is another top, front, right perspective view thereof, but shown with a door feature opened for clarity of illustration; and,

FIG. 10 is an exploded bottom, back, left side perspective view thereof, shown disassembled for completeness of illustration.

The broken lines in the drawings depict portions of the pet feeder that form no part of the claimed design.

1 Claim, 10 Drawing Sheets
